CLAIM

The ornamental design for an expandable dish drying rack as shown and described.

DESCRIPTION

FIG. 1 is a top perspective view of my new design showing a first configuration of an expandable dish drying rack;

FIG. 2 is a bottom perspective view thereof;

FIG. 3 is another top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a top perspective view showing a second configuration of the expandable dish drying rack;

FIG. 11 is a bottom perspective view thereof;

FIG. 12 is a top perspective view of the expandable dish drying rack of FIG. 1 showing a first environment of use;

FIG. 13 is a top perspective view of the expandable dish drying rack of FIG. 10 showing a second environment of use;

FIG. 14 is another top perspective view of the expandable dish drying rack of FIG. 1 showing a third environment of use; and,

FIG. 15 is another top perspective view of the expandable dish drying rack of FIG. 10 showing a fourth environment of use.

The broken lines in the FIG. 1-11 are for the purposes of illustrating portions of the expandable dish drying rack and the broken lines in the FIG. 12-15 are directed to environment that form no part of the claimed design.

1 Claim, 13 Drawing Sheets
